INDICATING MECHANISM FOR CASH
REGISTERS

Frederick L. Fuller, West Orange, N. J., assignor
to International Business Machines Corpora-
tion, New York, N. Y., a corporation of New
York

Original application June 26, 1936, Serial No.
87,333. Divided and this application May 4,
1937, Serial No. 140,631

5 Claims. (Cl. 235—23)

This application is a division of the parent ap-
plication Serial No. 87,333 filed June 26, 1936.

This invention relates to improvements in in-
dicating mechanisms for cash registers or the
like and relates particularly to improvements in
indicating mechanisms utilizing indicators of the
flat tablet type.

It is the main object of the present invention
to provide an indicating mechanism utilizing
10 tablets and an improved selecting mechanism for
causing the exhibition of tablets indicating the
amounts entered in the cash register.

A still further object of the present invention
is to provide an improved form of indicating
15 mechanism and indicator selecting mechanism
and to arrange the groups of indicators within
the machine and to operate them in such a man-
ner that the amount of the transaction, the
transaction, and the clerk's initial will be ren-
dered visible from both sides of the machine,
20 and the amounts exhibited in correct denomina-
tional order.

Another object of the present invention is to
provide an improved means for causing the se-
25 lection of related indicators in the two groups
facing oppositely, such means comprising pairs
of rack slides and a tube and shaft line for
connecting the related pairs of slides for simul-
taneous elevation. Each of a related pair of
30 slides is provided with a lifting finger for the
elevation of an indicator tablet in each group.

A still further object of the invention is to
provide a common support comprising spaced
35 plates which support the duplicate sets of indi-
cator tablets and a novel and improved means
for slidably carrying the sets of indicator tablets.

A still further object of the invention is to
provide an arrangement for carrying the rack
40 slides, and the tube and shaft line between the
spaced support plates and to further provide
means above the support plates to carry a U-
shaped indicator plate and within this indicator
plate the elevated slides project but are con-
cealed from view. The above described mount-
45 ing provides for unit construction and assembly.

Other objects and advantages will be apparent
as the specification is understood and which is to
be taken in connection with the drawings in
which:—

50 Fig. 1 is a front view of the exterior of the
machine.

Fig. 2 is a transverse sectional view taken on
the line 2—2 of Fig. 1.

55 Fig. 3 is a view in side elevation taken on the

line 3—3 of Fig. 2 showing some of the operating
connections for the indicating mechanism.

Fig. 4 is a detail view in side elevation showing
the preferred means for releasing previously ele-
vated tablets.

Fig. 5 is a sectional view taken on the line 5—5
of Fig. 7 and on an enlarged scale.

Fig. 6 is an enlarged detail view of one group
of indicator tablets and the supporting means
therefor.

Fig. 7 is a view in front elevation of the indi-
cating mechanism and is taken on the line 7—7
of Fig. 2.

Manipulative entry control devices

The machine includes three denominational
groups of amount keys, shown best in Fig. 1, the
numerical 10 designating the group for entering
cents, numerical 11 designating the group for en-
tering dimes, and numerical 12 designating the 20
group for entering dollars.

In addition to these keys there is a key 13
designated "Cash," a key 14 designated "Paid
out," a key 15 designated "Rec'd on acc't," a key
16 designated "No sale" and a key 17 designated 25
"C'h'g." This group of keys comprises the trans-
action control keys.

For the selective entry of amounts according to
a clerk's classification there is provided an "A"
clerk's key 18, and a "B" clerk's key 19.

The keys of the groups of amount keys are
depressed according to the amount to be entered,
the clerk's keys according to which clerk enters
the amount, and the transaction keys according
to the type of transaction, as is well known and 35
understood.

Each of the keys selected for operation is man-
ually depressed prior to an operation of the ma-
chine which is effected by a transverse operating
bar 20 and a key is locked in its depressed posi-
tion by a construction now to be explained in de-
tail for the group of dimes' keys 11, although it
is to be understood that a similar construction
is utilized for the other groups of keys.

The keys in each line from front to back are 45
offset laterally as shown in Fig. 1 to provide for
a convenient manual manipulation and to also
permit the lateral spacing of their respective in-
dicator selecting members, to be referred to in
detail hereinafter.

The stem of each key passes through a related
slot in a cover plate 24 (Fig. 2) and is further
guided by a slot in a U-shaped plate 25. Each
key is held in its normal outward position by a
spring 28 but when the key is depressed inwardly 55

a notch 29 thereof is caught by a detent plate 30 of the respective bank of keys. As shown in Fig. 2 each detent plate is carried by a pair of arms 31 pivotally mounted at 33. It is to be understood 5 that there is a detent plate for each group of keys.

Main operating bar

The main operating bar comprises a pair of arms 53 loosely pivoted on a stationary rod 55 10 and between which arms is carried outside of the machine the bar 20, and within the machine bars 33 and 69. When the bar 20 is rocked the arms 53 rock about the rod 55 and against the action of a return spring 56, connected to one of the 15 arms 53.

Key releasing devices

It is, of course, necessary to release the depressed keys after an operation of the machine 20 and as best shown in Fig. 2 each detent plate has secured thereto a bracket plate 34 to which is pivoted at 36 a spring urged pawl 35. A coil 25 spring 37 urges the pawl 35 counterclockwise so that a curved portion 38 normally hooks under the bar 39. During the initial depression of the 30 bar 39 the pawl 35 will be rocked clockwise idly until the curved portion 38 is free of the bar 39 whereupon the spring 37 will rock the pawl 35 counterclockwise but now with the curved portion 35 above the bar 39.

When the bar 39 has been fully depressed and then returned the bar 39 will in its elevation strike the curved portion 38 elevating the pawl 35 since the line of force acts through the center 35 of the pivot 36. This will cause the rocking of the detent plate 30 about its pivot 33 disengaging the detent plate 30 from the notch 29 of the depressed key releasing it for its return to normal by its spring 28. The continued elevation of the 40 pawl 35 will by a straight edge 40 of the latter coacting with a stationary rod 41 cause the pawl 35 to be rocked clockwise with the curved portion 38 now sliding to the left over the bar 39 until it is free of the bar. The spring 37 is now effective 45 to rock the pawl 35 to the normal position shown in Fig. 2.

Indicator selecting devices

As best shown in Fig. 2 pivoted at 66 to each 50 key stem is a key lever 67 having a coupling notch 68 engageable with the coupling bar 69 when the associated key is depressed. When the key lever 67 is coupled to the bar 69 the depression of the operating member 20 will cause the key lever to 55 be rocked and thus elevate an indicator tablet of an indicating mechanism now to be described.

Indicating mechanism

The present machine is provided with an indicating mechanism which will exhibit the amount 60 of each transaction, the type of transaction, and the clerk making the sale. This mechanism is best shown in Figs. 3, 4, 5, 6 and 7. The indicating mechanism for the most part is carried by 65 two side plates 280 and 281 (Fig. 5) which are attached to the side frames of the machine. These side plates are connected together at the top by a cross plate of a bracket 282. The side plates 280 and 281 carry transverse brackets 70 283 and 284.

The plates 280 and 281 carry various groups of indicators and Fig. 6 will be referred to as an example of the construction of the indicating mechanism.

75 The indicators are of the flat tablet type and

each comprises a tablet 285 having an upper indicia bearing portion 286 and a lower slotted portion 287. Each indicator has an aperture 289 adapted to receive an indicator elevating member or finger 288. For each amount group there 5 is, in one set, of course, nine indicator tablets 285 and each tablet has a related elevating member or finger 288. These fingers are preferably all the same length and to have the finger 288 10 cooperate with the aperture 289 of the "1" tablet, said finger must project through the other eight tablets of the related set. To permit this and still prevent the finger 288 from elevating unwanted tablets the latter are provided with slots, the slot 290 15 designating the slot in the "2" indicator tablet and other tablets so that the finger 288 can pass through and be elevated without raising undesired indicator tablets.

To confine the sets of tablets against the side plates 280 and 281 there is provided as shown in 20 Fig. 6 for one set two sets of headed screws 291 and 292 and which also guide the tablets in their elevation. When a previously elevated tablet is released it will drop to normal position by virtue of its own weight.

Considering, now the manner in which each group of amount keys selectively elevates the indicator tablets of the related set reference will be made to the dollars' bank of keys and the related set of indicators 293 shown in Fig. 5 30 and visible from the front of the machine.

It will be recalled that the key lever 67 of a key is shifted to the rear when the related key is depressed thereby moving a finger 294 (Fig. 5) 35 thereof beneath a stud 295 of the related indicator elevating rack slide of the dollars' group of rack slides 296 (Fig. 7).

The rack slides 296 are slidably mounted at their lower ends by slots 297 (Fig. 5) in the bracket plates 283 and 284 and at their upper 40 ends project through and are guided by slots in the cross plate of the bracket 282 and/or the overturned portions of the side plates 280 and 281. The finger or indicator elevating member 288 previously referred to comprises a plate riveted 45 at 298 to the related rack slide 296.

Obviously when, for example, the cam plate 67 related to the \$9 key is elevated the rack slide designated 296\$9 will be elevated and its finger 50 288 in Fig. 7 will be raised to the dotted line position (Fig. 5) raising the \$9 indicator of the front set, as shown by dotted lines in Fig. 5.

Obviously there must be provided means to hold the tablet in elevated position and this is 55 effected for all the rack slides of all groups which are elevated by key levers 67 by a spring-pressed bail 299 secured to a shaft 300. A cam edge 301 at the lower part of each rack slide 296 cams the bail 299 rearwardly and ultimately will overlie 60 the bail 299. When the key lever 67 is restored the rack slide will drop slightly until the rack slide 296 rests on the bail 299, as is shown in Fig. 2, holding the tablet in elevated position where it can be read.

In a similar manner the group of rack slides 302 (Fig. 7) for the dimes' bank will elevate the selected tablets of a dimes' set of indicators which are visible from the front of the machine and also the group of rack slides 303_F for the cents' bank 70 will elevate the selected tablets of a cents' set of indicators which are visible from the front of the machine.

It is, however, desirable to provide an indicator setting readable from the back of the machine 75

and to this end there is provided three sets of amount indicating tablets readable from the back of the machine and in correct numerical order, providing what is known in the art as "commercial indication." The set of indicators for the cents group is designated by numeral 304 in Fig. 5 and from this it will be seen that the front and back sets are similar in construction.

Since the amount entered was \$9 in the example assumed it is obviously necessary to select a \$9 indicator of the back set of dollars' indicators. Referring to Figs. 5 and 7 it will be seen that the rack slide designated 296\$9 is provided with rack teeth 305 meshing with a pinion 306 attached to a shaft 307 which carries at the other end a pinion 308 in mesh with rack teeth 309 of a rack slide designated 296\$9_B. This rack slide is also provided with a finger (not shown) but like finger 288 (Fig. 5) except that it projects through the back set of dollars' indicators and will elevate the \$9 indicator of the back set. Since the rack slide 296\$9 is held elevated it will hold the rack slide 296\$9_B elevated to hold the indicator of the back set in elevated position.

A similar arrangement is provided between the remaining rack slides of the front group 296_F of the dollars' indicator at the front and the rack slides of the back group 296_B for the dollars' indicators at the back, as shown in Fig. 7. The tube connections are arranged in three sets, 310, 311, 312 and comprises for each set; a shaft with pinions at each end; a tube overlying the shaft and provided with pinions at each end, and a second tube overlying the first tube and carrying pinions at each end. These connections are carried by the bracket plate 282.

Hence, the exhibition of the dollars' amount will be effected for each side of the machine. In Fig. 3 there is also shown the similar connections carried by the bracket plate 282 between the rack slides 303_F for the front set of cents' indicators and the rack slides 303_B for the back set of cents' indicators, so that the cents' amount can be exhibited on both sides of the machine and in proper numerical order.

The cross connections between the two sets of front and back indicators are only necessary for the cents and dollars. For the dimes the set of rack slides 302 is not provided with any rack teeth but each carries oppositely projecting fingers 288 (see Figs. 3 and 7), one finger projecting through the front set of dimes' indicators (Fig. 7) and the other finger through the back set (Fig. 3) of dimes' indicators. This will cause a pair of indicators representing the same "tens" amount to indicate similar amounts at the front and back.

A somewhat similar tablet selecting arrangement described for the "dimes" indicators is provided for the transaction set of indicator elevating slides 313, and the "B" indicator slide 314 (Fig. 7).

Attached to the plates 280 and 281 is U-shaped indicator plate 315 carrying the characters shown in Fig. 7. The pair of "B" indicators will change the normal clerk's indication "A" to "B" on both sides of the machine. A pair of selected transaction indicators will change the normal indication "Cash" to indicate some other type of transaction on both sides of the machine. The "\$" sign on the plate 315 will only be concealed when the dollars' indication is necessary. The two zeros on the plate 315 will fill in the zeros when only a dollars' indicator is exhibited.

As best shown in Fig. 5 the various rack slides, cross connecting means, etc., are located between

the plates 280 and 281 and concealed from view while the projected rack slides pass within the U-shaped plate 315 and are also concealed from view.

It is necessary, of course, to release the indicator tablets previously elevated and this is effected by the following described means.

As best shown in Fig. 4 one arm 53 has a pin and slot connection 316 to an extension 317 of an arm 318 loosely pivoted on the rod 41. Pivoted at 319 to the arm 318 is an irregular shaped pawl 320 and connected between a stud 321 carried by a tail 322 of the pawl and a stud attached to the arm 318 is a spring 323. In the normal position of the parts the stud 321 rests upon the upper edge of a bracket 324 the spring 323 being above the pivot 319 of the pawl so that the pawl is rocked to cause a cut-out portion 325 to engage a stud 326 carried by a link 327. The stud 326 receives a slot formed in the end of the arm 318.

At the initial operation of the machine the arm 318 is rocked by the arm 53 elevating the pawl 320 until a cam edge 328 thereof engages with a pin 329 carried by a side arm 330 of the bail 299. Further elevation of the arm 318 will cause the cam edge 328 to rock the bail 299 counterclockwise (Fig. 4) to release the previously elevated indicators. Further elevation of arm 318 will cause the pawl 320 to pass by the bail 299. When the arm 318 is restored a tail 331 of the pawl 320 will catch over the pin 329 but the pawl will merely rock idly in a clockwise direction until it is free of said pin, after which its pin 321 will engage with the bracket 324 and position the pawl 320 as shown in Fig. 4.

35

Flash mechanism

It is desirable to conceal the indicators while they are being elevated and for this purpose a flash mechanism is utilized and which is well known in the art. To this end there is provided the link 327 (Figs. 4 and 7) at the left end, and a similar link 332 (Fig. 7) at the right end and which latter has a pin and slot connection to the related arm 53 similar to that shown in Fig. 4 between the link 327 and the arm 53. Each link 327 and 332 carries at its upper end a Y-shaped piece 333 (Fig. 5) each Y-shaped piece having arms 334 and 335 projecting through slots 336 (Fig. 6) in the plates 280 and 281. Each pair of arms 334 and 335, carries a flash indicator plate 337 and both flash indicators pass up in front of all the sets of indicators, both front and back when the operating bar is depressed. Each indicator plate 337 preferably carries the words "Not registered" and by this arrangement the raised indicator tablets cannot be viewed until the flash indicator is lowered.

While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a cash register, a frame plate, a group of tablet indicators, guide means carried by said frame plate for slidably guiding said tablet indicators, and a corresponding number of individual tablet indicator elevating slides provided with fingers each of which is engaged with a related

75

- indicator and movable upwardly by the elevation of the related slide for raising the related indicator, the remaining tablet indicators being provided with slots through which said finger moves to prevent their elevation.
5. 2. In an indicating mechanism for a cash register or the like the combination with an inverted U-shaped frame comprising a top portion and two side plates, a plurality of groups of vertically movable indicators, there being two groups for exhibiting the same character at opposite sides of the machine, means carried by both of said side plates for slidably carrying said groups of indicators, means for causing the simultaneous elevation of the same character representing indicator in two groups comprising pairs of indicator elevating rack slides slidably mounted between said side plates, means for interconnecting related pairs of rack slides for simultaneous movement comprising for each pair of rack slides a shaft carrying pinions meshing with a related pair of rack slides, and means for carrying said interconnecting means by said U-shaped frame and between said side plates.
10. 3. The combination with an inverted U-shaped frame plate including a top plate and spaced parallel side plates, a plurality of groups of indicator tablets, means for carrying said groups of indicator tablets on opposite sides of said plate, vertically movable tablet elevating devices comprising pairs of rack slides, means comprising for each pair of rack slides a shaft carrying pinions meshing with a related pair of rack slides for causing the simultaneous elevation of the same character representing tablet in two groups for front and rear indication, and an inverted U-
- shaped indicator plate on said top portion for receiving the vertically movable tablet elevating devices but concealed from view, said U-shaped plate carrying indicia which are normally exhibited but which are concealed by the elevated tablets.
15. 4. In a machine of the class described, the combination with two groups of vertically movable indicators, of a group of rack slides each for causing the elevation of a selected indicator in one group, a corresponding number of supplemental rack slides of another group each for causing the elevation of a selected indicator in the other group of indicators, and means for interconnecting said group of rack slides and said supplemental rack slides comprising for each rack slide of the first named group and a corresponding supplemental rack slide of the other group a shaft carrying pinions meshing with said rack slides for causing the latter to elevate two indicators exhibiting the same value in both groups.
20. 5. In a machine of the class described, the combination with a plurality of depressible keys, of a group of vertically movable indicators, a common operating member operated manually and independent of said keys, a plurality of indicator elevating devices pivoted to and shifted by said keys, and connecting means provided for each of said indicator elevating devices for connecting the indicator elevating device shifted by a related key with said common operating member whereby an operation of the latter rocks the indicator elevating device about its pivot to elevate the related indicator.

35. FREDERICK L. FULLER.
